(57) **CLAIM**

The ornamental design for a display container, as shown and described.

DESCRIPTION

FIG. 1 is a top, front perspective view of a first embodiment of the display container, showing our new design;

FIG. 2 is a front view thereof;
FIG. 3 is a rear view thereof, opposite that shown in FIG. 2;
FIG. 4 is a side view thereof;
FIG. 5 is a side view thereof, opposite that shown in FIG. 4;
FIG. 6 is a top plan view thereof;
FIG. 7 is a bottom plan view thereof;
FIG. 8 is a top, front perspective view of a display container as shown in FIGS. 1-7 with the top perforated panels removed, and with environmental contents;
FIG. 9 is a top front perspective view of a display container as shown in FIGS. 1-7, with the top and bottom perforated panels removed, and with environmental contents; and
FIG. 10 is a top, front perspective view of FIG. 8, shown in an exemplary environment of relative size.
FIG. 11 is a top, front perspective view of a second embodiment of the display container, showing our new design;
FIG. 12 is a front view thereof;
FIG. 13 is a rear view thereof; opposite that shown in FIG. 12;
FIG. 14 is a side view thereof;
FIG. 15 is a side view thereof; opposite that shown in FIG. 14;
FIG. 16 is a top plan view thereof;
FIG. 17 is a bottom plan view thereof;
FIG. 18 is a top, front perspective view of the display container of FIGS. 11-17 in an exemplary environment; and,
FIG. 19 is a top, front perspective view of a display container as shown in FIGS. 11-18 with the perforated panels removed, and with environmental contents.
Throughout the drawings, the dash-dash broken lines are for the purpose of illustrating perforations that form a part of the claimed design. The dot-dot dash-dot lines are for the purpose of illustrating environment only and form no part of the claimed design.

1 Claim, 17 Drawing Sheets
